HEAT CONTROL RADIATOR VALVE

Clayton A. Dunham, Glencoe, Ill., assignor to
C. A. Dunham Company, Marshalltown, Iowa,
a corporation of Iowa

Application November 11, 1929, Serial No. 406,417

12 Claims. (Cl. 277—29)

This invention relates to new and useful improvements in heat control radiator valve, and more particularly to an improved form of inlet valve for controlling the flow of steam to a radiator or group of radiators in a steam heating system.

It is a well known fact that the rate of steam flow through an orifice will depend upon the size of the orifice and also upon the pressure difference existing between the two sides of the orifice. With an orifice of constant size, the steam flow may be increased by increasing the pressure difference between the two sides of the orifice. On the other hand, with a constant pressure difference existing between the two sides of the orifice, the steam flow may be increased by increasing the size of the orifice and decreased by decreasing the size of the orifice. In some systems of steam heating, a substantially fixed pressure difference is maintained between the supply and return sides of a radiator or radiating unit, just sufficient to maintain the required flow of steam into the radiator and to withdraw the non-condensable gases and condensates therefrom. The pressure of the steam supplied to the radiator may be atmospheric, or may be above or below atmospheric pressure, or the pressure may be varied in accordance with the heat radiation desired, but the pressure in the return piping is maintained lower than this supply pressure by a predetermined substantially constant amount. In such a system, the relative rates of steam flow into the several radiators will depend upon the relative sizes of the supply piping, and upon the relative sizes of any restricting orifices through which the steam must flow in order to enter the respective radiators. It is desirable to maintain a proper balance in the supply system, that is maintain a reservoir condition in the supply piping by keeping the velocity throughout the entire steam supply piping at relatively low values so as to secure a practically uniform pressure drop between the source of supply and each individual radiator. Since commercial pipe sizes vary by relatively large amounts it is difficult to properly select the supply piping so as to secure the desired balance, and accordingly orifice plates of proper size may be inserted in the piping in advance of each radiator or group of radiators to provide the proper balance in the system. The area of this orifice will depend upon the size or capacity of the radiator, and its position in the heating system. This principle has been used in the sub-atmospheric heating systems covered by the 55 patents granted to Clayton A. Dunham, No.

1,644,114, dated October 4, 1927, and 1,706,401, dated March 26, 1929.

The present invention relates to improved means for increasing or decreasing the quantity of heat or rate of steam flow to each of the various radiators or radiating units, without otherwise disturbing the balance in the heating system. Frequently portions of a building are unoccupied and it is desirable to supply only sufficient heat to prevent them from reaching freezing temperatures or temperatures that would damage the water pipes and plumbing or other portions of the building. It may be desirable to cut down the heat supply to only a single radiator or to a group of radiators in a zoning system. Accordingly, the present invention provides improved means for varying the size of the orifice which controls the steam flow to each radiator or group of radiators, either above or below normal size, in accordance with the local heating conditions desired.

Furthermore, when a heating system is first installed the pipe lines contain considerable foreign material such as core sand which has not been entirely cleaned from the interior of the radiators, oil coatings which may have been placed within the pipes to prevent rusting during shipment and during the period that they are awaiting installation, and materials resulting from the packing used by the steam fitter to make tight pipe joints. After a system has been in operation, it is frequently desirable to flush out each individual radiator and the piping system to carry away such foreign materials so that they may be finally emptied into the sewer. With the usual type of inlet valve provided with a fixed regulating plate or orifice it is difficult to accomplish this object. The present invention contemplates means for entirely removing the restricted orifice from the path of steam flow under such conditions without removing or dismantling the inlet valve.

More specifically, the present invention contemplates an inlet valve including a normally closed main cut-off valve, such valve being provided with a normally open auxiliary steam passage therethrough which serves as the restricting orifice. Means operable from outside the valve casing permit the enlargement or contraction of this orifice within certain limits so as to vary the rate of steam flow to the radiator. Means are also provided whereby an abnormal movement of this operating means will serve to open the normally closed main valve so that a free flow of steam or other fluid through the piping system

110

may be permitted in order to flush out the system or for any other purpose.

The principal object of this invention is to provide an improved form of steam inlet valve such 5 as briefly described hereinabove and disclosed more in detail in the specifications which follow.

Another object is to provide improved means whereby the heat supply to any individual radiator or group of radiators may be varied within 10 predetermined limits.

Another object is to provide an improved inlet valve comprising a normally closed main valve and a normally open auxiliary steam passage, combined with means for alternatively varying 15 the size of the auxiliary steam passage or opening the main valve.

Another object is to provide an improved form of indicating device positioned outside the valve casing for indicating the normal open position 20 of the flow control members, and the amount of variation from this normal position to which the valve may be adjusted.

Another object is to provide improved means for adjusting the indicating apparatus after the 25 valve has been installed in the system.

Another object is to provide an improved valve of the type hereinabove referred to, involving readily interchangeable thimbles whereby the normal opening of the orifice or steam passage 30 may be varied in accordance with the positioning of the valve in the heating system or the size of the radiator supplied therethrough.

Another object is to provide improved means whereby the restricted fluid passage may be enlarged to permit the piping and radiating system 35 to be flushed out.

Other objects and advantages of this invention will be apparent from the following detailed description of one approved form of apparatus 40 capable of carrying out the principles of the invention.

In the accompanying drawings:

Fig. 1 is a plan view of the valve.

Fig. 2 is a longitudinal vertical section, taken 45 substantially on the line 2—2 of Fig. 1.

Fig. 3 is a detail vertical section, taken substantially on the line 3—3 of Fig. 1.

Figs. 4, 5, 6, 7 and 8 are similar views showing 50 in central vertical section a series of interchangeable thimbles designed for use in this valve.

Referring now to the drawings, the improved form of inlet valve will be described in detail. The valve casing 8 houses the main valve chamber 9 which is separated by internal web 10 through which is formed the main steam passage 11, from the inlet passage 12 in the downward extension 13 of casing 8, this extension being internally threaded at 14 to engage with the upper end of the supply pipe or riser through which 55 steam is supplied to the radiator. The steam outlet passage 15 is contained in the lateral extension 16 of casing 8, and communicates with the nipple 17 which is externally threaded at 18 to be secured within the inlet opening of the 60 radiator. An adjustable union between the nipple 17 and outlet extension 16 is provided by the collar 19 which is internally threaded at 20 to engage suitable threads formed on the outer end of extension 16, the collar 19 having an internally extending shoulder 21 adapted to engage 65 behind an outwardly projecting annular shoulder 22 on the inner end portion of nipple 17. The inner end of nipple 23 fits adjustably within the outlet end of extension 16 thus providing a 70 limited amount of angular adjustability to facilitate

connecting up the valve with the riser and radiator. The upward extension 24 of casing 8 is externally threaded at 25 to engage similar internal threads in the bonnet 26.

The main valve member 27 will normally be 80 held down against the annular valve seat 28

formed on web 10 so as to close the main steam passage 11. Threaded at 29 into a central opening in valve member 27 is a thimble or bushing 30 having an auxiliary steam passage or orifice 85 31 formed therethrough. Thimble 30 may be provided with suitable notches 32 in its lower end for engagement with a tool whereby the thimble may be screwed into place or removed from the valve member 27. Thimble 30 is pro-

vided with an upwardly projecting sleeve portion 90 33 which may be externally beveled at 34. Thimble 30 may take a variety of forms and proportions, as shown for example in Figs. 4 to 8 in-

clusive, for reasons that will hereinafter be 95 apparent. Main valve member 27 has an outer upwardly projecting sleeve portion 35 formed at its upper end with an outwardly extending annular shoulder 36. The closure member 37 has

permanently secured thereto at its outer periphery a downwardly extending sleeve member 100 38 formed at its lower end with an inwardly ex-

tending collar or flange 39 adapted to slidably engage around the main valve member 27 be- 105 neath the shoulder 36 thereon. Closure member 105

37 is imperforate, but sleeve 38 is provided with a circumferential series of ports or openings 40 for permitting the flow of steam therethrough. An inner annular sleeve 41 projects downwardly 110 from closure member 37 so as to telescope down around the upwardly projecting discharge sleeve 33 on thimble 30. A compression spring 42 is confined between the upper surface of valve member 27 and the top of an annular groove formed in the lower surface of closure member 115 37. The compressed spring 42 serves to normally hold valve member 27 against the valve seat 28 in all normal positions of vertical adjustment of closure member 37.

It will now be apparent that the steam flowing 120 in through inlet passage 12 and the auxiliary steam passage 31 in thimble 30, must flow around through the annular passage formed between the sleeve members 33 and 41 on the thimble and closure respectively and thence out through ports 125

40 into the main valve chamber 9 from which it passes through outlet passage 15 and nipple 17 into the radiator. With a substantially constant pressure difference between the inlet and outlet 130 sides of the valve, the rate of steam flow and con-

sequently the volume of steam passing through the valve into the radiator will be determined by the size of the restricted orifice formed by the circuitous passage just described. By lowering 135

the closure member 37, the annular passage be- 140 tween the sleeves 33 and 41 will be decreased in area and the effective size of the orifice will be restricted. Conversely, by elevating the closure member 37 the effective size of the orifice will be enlarged.

In addition to this range of adjust- 145 ability provided by the raising or lowering of closure member 37, the normal rate of steam flow may be changed by varying the size of the aux-

iliary passage 31, and the proportions of the sleeve member 33 in thimble 30. As already 145 noted, Figs. 4 to 8 inclusive illustrate several alter-

native forms of thimble 30 that may be inter- 150 changeably positioned in the valve member 27. Fig. 4 illustrates a thimble 30a having a relatively small steam passage 31a and a relatively thick

sleeve portion 33^a, so as to provide a maximum restriction to the steam flow, this thimble being adapted for use with radiators of small capacity. In Fig. 8 is illustrated a thimble 30^e having a relatively large steam passage 31^e and a relatively thin sleeve member 33^e, this thimble being used for a radiator of large volume or capacity, requiring a large inflow of steam to replace the steam condensed therein. In a similar manner, Figs. 5, 6 and 7 show intermediate forms of thimbles adapted for radiators of intermediate size. It will now be seen that all other members of the valve structure may be made of standard size and proportions, and that by inserting the proper thimble 30 the valve may be adapted for use with any standard size or type of radiator. Obviously, there may be a great many more sizes of thimbles 30 provided than those shown by way of example in Figs. 4 to 8 inclusive. By selecting the proper thimble 30 for use in the valve, the approximately correct normal steam flow may be obtained, and any necessary finer adjustment may be obtained by a proper setting of the adjustable valve mechanism as hereinafter described.

A flexible corrugated sealing diaphragm or packing 43 is sealed at its lower end 44 to the outer upper edge of closure member 37, and at its upper end has an outwardly extending flange 30 or ring 45 which is clamped between the upper edge of the ring extension 46 of casing 8 and the outer edge portion of the guide plate 47 which is held down by the annular shoulder 48 formed in bonnet 46. This flexible diaphragm member 43 forms, with the closure 37, a continuous imperforate upper wall for valve chamber 9 to prevent the escape of steam through the top of the valve chamber without interfering with the requisite vertical movements of the movable valve members and the operating mechanism therefor. The particular form of sealing diaphragm 43 here illustrated, is disclosed more in detail and claimed in the copending application of Brennan and Wilding, Serial No. 412,861 filed December 9, 1929, now Patent No. 1,830,780, granted November 10, 1931.

The ring extension 46 might be formed as an integral part of valve casing 8, but is here shown as a separate member in order that valve casings of standard type already in use may be adapted for this new valve by merely adding the extension ring 46 whereby the necessary additional upward movement of the valve mechanism is permitted.

The valve stem 49 is provided at its lower end with a head 50 which is swiveled within a recess 51 formed in the central top portion of cover 37 and held in place by the flange 52 which is spun inwardly over the head 50. The upper portion 53 of valve stem 49 has flattened sides or is of other non-circular form, and is vertically slidably through a passage 54 of similar contour formed in the guide plate 47 whereby valve stem 49 is held against rotation without interfering with its vertical movements. An internally threaded nut 55 is positioned above the guide plate 47 and is held in place by means of an outwardly extending annular flange 56 at its lower end engaging a similar shaped groove formed in bonnet 26. An externally threaded nut 57 is engaged within the threads formed in nut 55, this nut 57 being formed with a T slot 58 in which is engaged the correspondingly shaped head 59 on valve stem 49, whereby the valve stem and nut 57 are coupled together without capacity for relative rotative movements. Either single or multi-

ple engaging threads may be formed on the nuts 55 and 57, and these threads will be of rather large pitch so that a comparatively small rotative movement of nut 55 will produce a comparatively large vertical movement of the non-rotatable nut 57. It will now be apparent that as the nut 55 is rotated or oscillated, the internal valve members 37 and 27 will be raised or lowered by means of the nut 57 and valve stem 49.

The nut 55 is provided with a circumferential series of external vertically extending teeth 60 (see Fig. 2) which are interengaged with a corresponding internal set of vertical teeth formed in the ring or operating head 62 which surrounds the nut 55. The ring or head 62 is normally secured in place about the nut 55 by means of a locking screw 63 extending through the head into an annular groove 64 formed externally in the nut 55. It will be apparent that by unscrewing the locking screw 63 the head or ring 62 may be elevated with respect to nut 55, the teeth 60 sliding over one another so that the nut and ring will still remain locked together for simultaneous rotative movements.

A laterally projecting operating handle 65 of any suitable type is secured to operating head 62. An annular dial plate 66, in the form of a split metal ring, is adapted to be sprung into place in a groove 67 formed in the top portion of bonnet 26. Different positions on this dial are suitably marked as by "Normal", "Warmer", and "Cooler", and a pointer or indicating device 68 formed on ring 62, preferably at the side opposite the handle 65, is adapted to cooperate with these indications on dial 66 in order to show the position of the movable valve members. A stop pin or stud 69 is anchored in dial plate 66 at a point adjacent the "Warmer" designation, preferably by having its lower end riveted through the plate as indicated at 70 in Fig. 4. The upper surface of bonnet 26 is formed with an annular series of spaced depressions 71, into any one of which the lower end 70 of this stop member may be inserted in order to lock the dial plate 66 in different selected positions of rotary adjustment. The pointer or indicating finger 68 is adapted to engage the stop 69 to prevent further rotative adjustment of the operating mechanism in this direction when the closure member 37 has been lifted to the maximum extent permitted without lifting the main valve 27 from its seat 28. A closure plate 72 is adapted to be seated in the upper surface of ring or head 62, and this closure plate may serve as a name plate or carry other inscriptions. A stop shoulder 73 formed on valve stem 49 is adapted to engage the under surface of guide plate 47 before nut 57 engages the closure plate 72, to prevent forcing this closure plate from its seat.

When properly installed, the bushing or thimble 30 will be so selected, and the indicating dial 66 will be so adjusted, that when the pointer or finger 68 is opposite the "Normal" indication on the dial the closure member 37 will be at a mid-position of vertical adjustment, and the size or area of the steam passage or orifice through the valve will be of proper size to permit a normal flow of steam through the valve into the radiator. When so adjusted the valve will function substantially the same as the open inlet valve and orifice plate disclosed in the Dunham patents hereinabove referred to. Now if it is desired to decrease the flow of steam into the radiator and thereby cut down its heating effect, it is merely necessary to rotate handle 65 in a clockwise direction 100

(Fig. 1) so as to move the finger 68 toward the "Cooler" indication, thus lowering the closure member 37 and decreasing the size of the steam orifice through the valve. This movement may 5 be continued if desired until the sleeve members 33 and 41 completely telescope over one another so as to substantially cut off the flow of steam through the valve.

On the other hand, if more heat is desired, the 10 handle 65 is rotated in a counter clockwise direction so as to move the finger 68 toward the "Warmer" indication thus increasing the size of the steam orifice and permitting a greater flow of steam into the radiator. Under normal conditions, 15 all the steam that the radiator can condense should be permitted to flow through the valve when the valve is set at "Normal", but unusual temperature conditions or an unbalanced condition in the heating system may necessitate 20 the movement of the valve control member toward "Warmer" in order to permit an increase in the steam flow into the radiator. The finger or pointer 68 will engage the stop pin 69 before the overlapping flanges 39 and 36 on the relatively movable valve members have come into engagement, thereby preventing the lifting of main 25 valve member 27 from its seat 28.

In case it is desired to open the main steam passage 11 so as to permit the piping system and 30 valve to be flushed out, the locking screw 63 is unscrewed so as to permit the operating ring or head 62 to be elevated sufficiently to free the finger 68 from engagement with stop pin 69 so that the operating handle may be rotated further 35 in a counter clockwise direction (Fig. 1), whereupon the flange 39 on closure 37 will engage under the outstanding flange 36 on flange member 27 and lift this valve from its valve seat 28, thus opening the main steam passage 11 through the valve. After the system has been 40 flushed out, the valve ports may be returned to their normal positions by a mere reversal of the steps just set forth.

It will now be apparent that a heating system 45 of the type first set forth hereinabove will operate in the usual manner with all of these valves set at "Normal," the heat output of the several radiators being regulated by changing the sub-atmospheric pressure of the steam supplied 50 throughout the system. If, through faulty installation, or for any other reasons an unbalanced condition exists in any portion of the radiating system, this may be corrected by a simple adjustment of one or more of the several inlet 55 valves so as to slightly increase or decrease the rate of steam flow to the respective radiators. If, under special conditions, it is found desirable to more radically change the heat output of any radiator or group of radiators, this may be accomplished by a suitable adjustment of the valve 60 handle 65. If for example a certain room or group of rooms is to be unoccupied so that it is unnecessary to keep these rooms heated up to a normal temperature, the valve members may be 65 adjusted so as to permit only a limited flow of steam to the radiators just sufficient to prevent a dangerously low temperature from being reached in these rooms.

While this improved valve member has been 70 especially designed for use in a sub-atmospheric heating system, it will function in substantially the same manner in a heating system using steam at atmospheric pressure or at pressures above atmospheric. As long as a substantially constant 75 pressure difference is maintained between the

inlet and outlet sides of the valve, the rate of steam flow through the valve may be varied by the proper adjustment of the effective size of the steam passage or orifice in the valve.

Instead of, or in addition to, the use of one 80 of these valves at the inlet of each radiator in the system, a control valve of this type could be used before a group of radiators, or a branch of the radiating system as in a zoning system where different temperatures or heat outputs are to be simultaneously maintained in different portions of a building. In such case, the valve will function to regulate or adjust the steam flow to the group of radiators or a zone in the same manner as hereinabove described in connection 85 with a single radiator.

I claim:

1. In a steam heating system, an inlet valve comprising a valve casing provided with inlet and outlet openings and a main steam passage intermediate said openings, a valve seat surrounding said passage, a main valve member normally engaging the valve seat, said valve member having a normally open flow control passage therethrough, and means operable from outside the 100 casing for increasing or decreasing the effective size of this flow control passage, or for lifting the main valve from its seat to open the main steam passage, and stop means for normally limiting the movement of this latter operating 105 means so that the main valve will remain closed.

2. In a steam heating system, an inlet valve comprising a valve casing having inlet and outlet openings and a main steam passage therebetween, a normally closed main valve controlling this 110 passage, a normally open auxiliary steam passage in the main valve and means for variably controlling the flow of steam through the auxiliary passage and for opening the main valve including an operating handle positioned outside the cas- 115 ing, a pointer on the handle, a dial mounted on the casing and cooperating with the pointer to indicate the normal position of the valve mechanism and the amount of adjustment from this normal position and means for adjusting the position of the dial on the casing.

3. In a steam heating system, an inlet valve comprising a valve casing having inlet and outlet openings and a main steam passage therebetween, a normally closed main valve controlling this 125 passage, a normally open auxiliary steam passage in the main valve and means for variably controlling the flow of steam through the auxiliary passage and for opening the main valve includ- 130 ing an operating handle positioned outside the casing, a pointer on the handle, a dial mounted on the casing and cooperating with the pointer to indicate the normal position of the valve mechanism and the amount of adjustment from this normal position, a stop carried by the dial in 135 position to be engaged by the pointer when the auxiliary passage has been increased to its maximum opening, and means for moving the pointer out of engagement with the stop so that a continued movement of the handle may be utilized 140 to open the main valve.

4. In a steam heating system, an inlet valve comprising a valve casing having inlet and outlet openings and a main steam passage therebetween, a normally closed main valve controlling this 145 passage, a normally open auxiliary steam passage in the main valve and means for variably controlling the flow of steam through the auxiliary passage and for opening the main valve includ- 150 ing a rotary member projecting from the casing,

- a handle keyed to the rotary member to impart rotation thereto, a pointer on the handle, a dial fixed to the casing and cooperating with the pointer to indicate the position of adjustment of 5 the valve mechanism, a stop on the dial engaged by the pointer when the auxiliary passage has been increased to its maximum opening, the handle and pointer being slideable on the rotary member away from the casing to move the pointer out 10 of engagement with the stop whereby further rotation of the handle and rotary member will open the main valve.
5. In a steam heating system, an inlet valve comprising a valve casing having inlet and outlet openings and a main steam passage therebetween, a normally closed main valve controlling this passage, a normally open auxiliary steam passage in the main valve and means for variably controlling the flow of steam through the auxiliary passage and for opening the main valve including an operating handle positioned outside the casing, a pointer on the handle, an annular dial plate mounted on the casing and cooperating with the pointer to indicate the normal position of the valve mechanism and the amount of adjustment from this normal position, a stop pin fixed in the dial plate and having portions projecting above and below the plate, the pointer engaging the upper portion of the pin when the auxiliary passage has been increased to its maximum opening, there being a series of spaced sockets in the valve casing beneath the dial plate to be alternatively engaged by the lower portion of the stop pin to lock the dial plate in adjusted position on the casing.
6. In a steam heating system, an inlet valve comprising a valve casing provided with inlet and outlet openings and a main steam passage intermediate said openings, a valve seat surrounding said passage, means cooperating with said valve seat to close said steam passage comprising a main valve member engaging the seat and having an auxiliary steam passage therethrough, a cupped closure member movable over said main valve member and having a steam passage leading thereinto, and cooperating flow control devices on the valve member and closure member to determine the steam flow through the members as the devices are moved toward or from one another, and means operable from outside the casing for moving the closure member toward or from the valve member.
7. In a steam heating system, an inlet valve comprising a valve casing provided with inlet and outlet openings and a main steam passage intermediate said openings, a valve seat surrounding said passage, means cooperating with said valve seat to close said steam passage comprising a main valve member engaging the seat and having an auxiliary steam passage therethrough, a cupped closure member telescopically engaging the main valve member and movable toward or from the valve seat, an expansion spring interposed between the closure member and valve member to normally hold the valve member against the valve seat, interengaging shoulders on the closure and valve members whereby the valve member will be lifted from its seat when the closure member is moved away from the seat more than a predetermined distance, there being steam passages leading into the closure member and cooperating flow control devices on the closure member and valve member to determine the steam flow through the members as the devices are moved toward or from one another, said devices including a plurality of thimbles alternatively engageable within the valve member, auxiliary steam passages of different sizes being formed in the respective thimbles, and a cooperating sleeve in the closure member adapted to telescopically engage the thimble, and means operable from outside the valve casing for moving the closure member toward or from the valve seat.
10. In a steam heating system, an inlet valve comprising a valve casing provided with inlet and outlet openings and a main steam passage intermediate said openings, a valve seat surrounding said passage, means cooperating with said valve seat to close said steam passage comprising a main valve member engaging the seat and having an auxiliary steam passage therethrough, spring means for normally holding the main valve closed, a movable closure having lost motion connections with the main valve member whereby opening movement of the movable closure beyond 150
- other and means operable from outside the valve casing for moving the closure member toward or from the valve seat.
8. In a steam heating system, an inlet valve comprising a valve casing provided with inlet and outlet openings and a main steam passage intermediate said openings, a valve seat surrounding said passage, means cooperating with said valve seat to close said steam passage comprising a main valve member engaging the seat and having an auxiliary steam passage therethrough, a cupped closure member telescopically engaging the main valve member and movable toward or from the valve seat, an expansion spring interposed between the closure member and valve member to normally hold the valve member against the valve seat, interengaging shoulders on the closure and valve members whereby the valve member will be lifted from its seat when the closure member is moved away from the seat more than a predetermined distance, there being steam passages leading into the closure member and cooperating flow control devices on the closure member and valve member to determine the steam flow through the members as the devices are moved toward or from one another, said devices including a thimble fitted within the valve member and in which the auxiliary passage is formed, and a cooperating sleeve on the closure adapted to telescopically engage the thimble, and means operable from outside the valve casing for moving the closure member toward or from the valve seat.
9. In a steam heating system, an inlet valve comprising a valve casing provided with inlet and outlet openings and a main steam passage intermediate said openings, a valve seat surrounding said passage, means cooperating with said valve seat to close said steam passage comprising a main valve member engaging the seat and having an auxiliary steam passage therethrough, a cupped closure member telescopically engaging the main valve member and movable toward or from the valve seat, an expansion spring interposed between the closure member and valve member to normally hold the valve member against the valve seat, interengaging shoulders on the closure and valve members whereby the valve member will be lifted from its seat when the closure member is moved away from the seat more than a predetermined distance, there being steam passages leading into the closure member and cooperating flow control devices on the closure member and valve member to determine the steam flow through the members as the devices are moved toward or from one another, said devices including a plurality of thimbles alternatively engageable within the valve member, auxiliary steam passages of different sizes being formed in the respective thimbles, and a cooperating sleeve in the closure member adapted to telescopically engage the thimble, and means operable from outside the valve casing for moving the closure member toward or from the valve seat.

- a predetermined normal range of movement will open the main valve in opposition to the spring means, means operable from outside the casing for moving the closure member, and cooperating flow control devices on the main valve member and closure member to determine the steam flow through the auxiliary steam passage as the closure member is moved through the normal range of movement.
- 10 11. In a steam heating system, an inlet valve comprising a valve casing provided with inlet and outlet openings and a main steam passage intermediate said openings, a valve seat surrounding said passage, means cooperating with said valve seat to close said steam passage comprising a main valve member engaging the seat and having an auxiliary steam passage therethrough, spring means for normally holding the main valve closed, a movable closure having lost motion connections with the main valve member whereby opening movement of the movable closure beyond a predetermined normal range of movement will open the main valve in opposition to the spring means, means operable from outside the casing for moving the closure member, and cooperating flow control devices on the main valve member and closure member to determine the steam flow through the auxiliary steam passage as the closure member is moved through the normal range of movement, said devices including a thimble fitted within the main valve member and in which the auxiliary passage is formed, and a cooperating sleeve on the closure member adapted to telescopically engage the thimble.
- 15 12. In a steam heating system, an inlet valve comprising a valve casing provided with inlet and outlet openings and a main steam passage intermediate said openings, a valve seat surrounding said passage, means cooperating with said valve seat to close said steam passage comprising a main valve member engaging the seat and having an auxiliary steam passage therethrough, spring means for normally holding the main valve closed, a movable closure having lost motion connections with the main valve member whereby opening movement of the movable closure beyond a predetermined normal range of movement will open the main valve in opposition to the spring means, means operable from outside the casing for moving the closure member, and cooperating flow control devices on the main valve member and closure member to determine the steam flow through the auxiliary steam passage as the closure member is moved through the normal range of movement, said devices including a thimble removably engaged within the main valve member, the thimble being formed with a steam passage therethrough of a size to determine the normal rate of steam flow through the valve, and a cooperating sleeve on the closure member adapted to telescopically engage the thimble.
